CLARENCE SAUNDERS, OF MEMPHIS, TENNESSEE, ASSIGNOR TO PIGGLY WIGGIE CORPORATION, OF MEMPHIS, TENNESSEE, A CORPORATION OF DELAWARE.

TAPE FOR ADDING-MACHINES.

1,380,081.

Specification of Letters Patent. Patented May 31, 1921.

Application filed December 10, 1917. Serial No. 206,503.

To all whom it may concern:

Be it known that I, CLARENCE SAUNDERS, a citizen of the United States, residing at Memphis, Shelby county, and State of Tennessee, have invented and discovered certain new and useful improvements in Tape for Adding-Machines, of which the following is a specification.

The object of my said invention is to provide a special tape for use with adding machines so constructed and marked that identification of every portion of the tape that passes through the adding machine will be certain, and the absence of any part of a complete tape can be readily detected by the auditing office. A further purpose is to insure absolute accuracy in checking up the tape with the amount in the cash drawer at any time. By the use of such a tape, and the system which it involves, a cash register can be dispensed with as a necessary part of a checking and settlement station in a store, and the expense thereof saved without dispensing with safeguards that are reliable, accurate and difficult to avoid.

In the accompanying drawings, I have illustrated a section of tape of the construction designed for the purpose, and in said drawings Figure 1 shows the tape as it is used, the illustration being a portion of said tape just after it comes out of the adding machine.

Fig. 2 illustrates the same portion of tape after it has passed through the cashier's hands, one part ready for passing to the customer with the package, and the other to be filed for the auditor's use.

Said tape consists of a strip of paper preferably mounted on a roll, after the usual custom, and may be adapted for use in any adding machine of standard make, in the usual way. Said tape is provided with a perforated line 10 extending at a point approximately midway its width from end to end the perforation being made in order to permit ready severance of the two parts of the tape and insure substantially equal division thereof. On one side of the said perforated line, arranged a short distance apart, are a series of identification characters or marks. In the tape illustrated, I have shown a series of numerals running from 47 to 50 and it is understood, of course, that these numerals run to indefinite num-

bers and are arranged in sequence. In front of each numeral I have a letter A. This may be used or not as preferred. If used, it is for the purpose of identifying a series of tapes. The letters may be used without the numerals, or any other identification characters may be employed as may be found desirable for the particular service to be provided for. The combination of letters and numerals shown enables an almost indefinite variety of identification marks, in series, to be provided.

The method of using this tape may be described as follows: The tape being manufactured with the identification characters on the left hand side of the perforated line, as shown, and each roll of tape having its own identification mark, each roll can be made of record in the auditor's office, or in any office having charge of the matter. When a certain store, or checking clerk, or cashier, is given a roll of tape, it is charged up so that the auditor knows the person and the machine and place to which the particular roll goes. The person at the store inserts the roll in the adding machine and said machine is then ready for use. The customer coming to the checking clerk with a number of purchases, the checking clerk adds up the prices of the items on the machine in the usual way. The machine records the prices of the individual articles on the portion of the tape on the side of the perforated line opposite that portion bearing the identification marks or characters. When the articles are all tabulated, the total is written immediately beneath, and this sub-total is preferably identified by a special character such as the letter S, as shown. The spacing mechanism is operated to move the tape a few spaces; approximately one inch, when the auditor clears the machine and operates it to imprint upon the tape the "clearance" total which corresponds to the sub-total above. One of the standard adding machines, as now equipped, indicates this clearance total on the tape by a star, as shown in the drawings. After this total is imprinted on the tape, the portion of the tape having the tabulation is torn off and handed to the customer. The customer takes the tape portion to the cashier, who is near at hand, and pays the amount indicated by the total. The cashier splits the tape down the perforated line 10 and at

5 a point between the sub-total and the clearance total tears it transversely handing the portion marked 11, in Fig. 2, to the customer and retaining the portion marked 12, which is filed for use in checking up the cash and auditing the accounts. The customer retains the portion marked 11, and taking his packages from the checking clerk, leaves the settlement station.

10 This system of checking has been devised particularly for use with self serving stores and as a part of such a system of merchandising, whereby a cash register can be dispensed with and the slips of tape 12 serve 5 the purpose for checking and auditing of the accounts, and the usual "overhead" expense thus materially reduced.

15 By this system, there is no way for "leaks" to develop in the store without collusion between the checking clerk in control of the adding machine, the customer himself and the cashier. The customer, being in the habit of receiving a tabulated list of his purchases, naturally would not be satisfied 20 should he not receive the tape belonging to him. The cashier, on the other hand, would not know the amount of money to collect from the customer unless the tape were handed in at the time of making settlement 25 for the purchases. The customer's portion of the tape can be retained by him as a ready means of keeping account of his purchases and checking up his own expenditures.

30 It is thus seen that the use of a cash register, and the tedious operation consequent upon its use, may be dispensed with, and in a busy place, where there are a number

of customers standing in line to be waited upon, the time required to punch the keys 40 of the cash register and wait for the cash drawer to open is saved, which means a saving of much time during a busy day's work in such a store and enables the store to wait upon a proportionately larger number of 45 customers. While a cash register provides no absolute check on the cash, this system does, as every slip is capable of identification, and any portion of the tape not turned in would be quickly missed by the auditor 50 because of these identification marks.

Having thus described my said invention, what I claim as new and desire to secure by Letters Patent is:

1. A tape for adding machines perforated longitudinally and having identification characters on one side and adapted to have tabulated records upon the other side and totaled with duplicate totals a distance apart, substantially as set forth. 55

2. A tape for adding machines formed with a longitudinal perforation, having a progressive series of identification characters arranged at intervals throughout the length of the tape, and on the other side a 60 blank for receiving the tabulated records and totals, substantially as set forth. 65

In witness whereof I have hereunto set my hand and seal at Memphis, Tennessee, this 5th day of December, A. D. nineteen 70 hundred and seventeen.

CLARENCE SAUNDERS. [L. S.]
